UNITED STATES PATENT OFFICE.

HORACE D. PARKE, OF SYRACUSE, NEW YORK.

IRONING-TABLE.

SPECIFICATION forming part of Letters Patent No. 273,140, dated February 27, 1883.

Application filed November 23, 1882. (No model.)

To all whom it may concern:

Be it known that I, HORACE D. PARKE, a citizen of the United States, residing at Syracuse, in the county of Onondaga and State of New York, have invented certain new and useful Improvements in Ironing-Tables; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a vertical sectional view of my device. Fig. 2 is a plan view of the stand folded, and Fig. 3 is a bottom view of the board.

This invention has relation to ironing-boards; and it consists in the construction and novel arrangement of devices, as hereinafter set forth, and particularly pointed out in the appended claims.

In the annexed drawings, the letters A A designate longitudinal ties or side bars, which are pivoted on bearings at the ends of transverse bars B, which are shouldered at c, and are secured to the standards D of the end frames, E, which form the supports. The end frames consist each of the standards D, cross-bars F and G, oblique braces H, the transverse bearing-bar B, and a transverse stop-bar, K, arranged on the inside of the frame, somewhat above the level of the bar B, so that when the supporting-frame is in the vertical position the stop-bar will engage the upper edges of the horizontal side bars, A, which are pivoted near the middle portion of each frame, as shown in the drawings.

L designates a middle transverse bar, which connects the horizontal side bars, A, and is provided with a catch-plate, m, which projects by its edges over the edges of the bar.

Hinged braces N are connected, one to each supporting-frame, and are provided with ratchet-plates p on their ends to engage the edges of the catch-plate when the stand is set up. The ratchet-plate p is formed with an end flange, r, which engages the end of the brace N, and is perforated to receive a fastening-screw. The serrations of the ratchet are formed on the oblique edge of an angular longitudinal rib, t, of the plate, so that the engagement with the catch-plate can be easily effected. The braces N are hinged to the lower cross-bars, G, of the supporting-frames, and

said bars are provided with spring-catches v, which, when the supporting-frames are folded against the longitudinal bars, serve to hold said frames in folded position. The upper cross-bar, F, of one of the supporting-frames is pivoted in the heads of the standards, and to this bar is attached, by means of pins z or screws, the ironing board or table a, which is braced across in the usual manner by means of cleats b. One end of the ironing-board is squared to provide a straight edge, c, and a short bosom-board, d, having a corresponding straight edge, c', is connected thereto by under hinges, d, so that when the bosom-board, which is of the same thickness with the ironing-board, is raised level therewith the edges c and c' will abut, and hold, by their crimping action, a fold of cloth introduced between them.

In order to effect a forcible clamping between the edges c and c', as well as to hold the bosom-board up, the latter is provided with a hinged brace, e, having a ratchet, g, along its end portion, designed to engage a catch-plate, m', on the stop-bar K. In ironing a shirt a fold of the cloth next the bosom is caught squarely between the edges c and c', so that the bosom can be evenly stretched.

This ironing-board, when set up in standing position, is very firm, owing to the opposite pressures of the hinged brace-bars and the stop-bars with reference to the horizontal bars.

Having described this invention, what I claim, and desire to secure by Letters Patent, is—

1. A folding ironing-board having the longitudinal side bars, A, connected by the middle cross-bar, L, the end supporting-frames, E, pivoted near their middle portions to the ends of the longitudinal bars, the transverse stop-bars K, the catch-plate m', and the hinged brace-bars N, having the ratchet-plates p, substantially as specified.

2. The combination, with the ironing-board having the squared edge c, and the end support, E, provided with a cross-bar, K, having a catch-plate, m', of the bosom-board, having a corresponding squared edge, c', under hinges, d, connecting it to the ironing-board, and a brace-arm, e, hinged thereto, and having a ratchet at its end, substantially as specified.

In testimony whereof I affix my signature in presence of two witnesses.

Witnesses: HORACE D. PARKE.
